Primary Examiner—James R. Largen*Attorney, Agent, or Firm*—John W. Overman[57] **CLAIM**

The ornamental design for a combination vanity and lavatory, substantially as shown and described.

DESCRIPTION

FIG. 1 is a front perspective view of a combination vanity and lavatory embodying our new design.

FIG. 2 is a top plan view thereof.

FIG. 3 is a front elevation view.

FIG. 4 is a side elevation view.

FIG. 5 is a sectional view taken along line 5—5 of FIG. 2.

The broken line representation of a drain connection in FIGS. 4 and 5 is for purposes of illustration only.
